Filed Aug. 8, 1969, Ser. No. 18,594

Term of patent 14 years

Int. Cl. D28—03

U.S. Cl. D86—10

FIG. 1

FIG. 2

FIG. 3

FIG. 1 is a front perspective view of a cosmetic case showing my new design;

FIG. 2 is a rear perspective view thereof; and

FIG. 3 is a front perspective view of the cosmetic case in an opened position.

The bottom of the cosmetic case is flat and plain.

The design is characterized by the combination, in a cosmetic case, of a lid having a raised rectangular portion on one side perpendicular to the hinge and overlying a raised interfitting rectangular interior portion of the case all as shown.

I claim:

The ornamental design for a cosmetic case, as shown and described.
